UNITED STATES PATENT OFFICE.

ALLEN B. ASHBY, OF BONNERS FERRY, IDAHO.

FORWARDING ENVELOPE.

Application filed May 2, 1921. Serial No. 466,113.

To all whom it may concern:

Be it known that I, ALLEN B. ASHBY, a citizen of the United States, residing at Bonners Ferry, in Boundary County and 5 the State of Idaho, have invented certain new and useful Improvements in Forwarding Envelopes, of which the following is a specification.

My present invention relates to improvements in forwarding envelopes designed especially for use in the mails when it is desired to forward a communication in a single packet to a succession of destinations, and finally returned to the sender or initial 10 source of travel, or to a predetermined destination. The primary object of the invention is the provision of an envelope of this character which has a succession of dispensible address sheets or leaves, each of which, 15 while in use as a part of the envelope, is utilized to seal the enclosed parts until they are utilized. And after the last auxiliary leaf has been utilized the envelope in its final 20 form affords a properly sealed and protected enclosure for the article inclosed.

With the above objects in view the invention consists in certain novel combinations and arrangements of parts and in the formation of the envelope blanks, as will be 25 hereinafter more fully pointed out and claimed.

In the accompanying drawings I have illustrated one complete example of the physical embodiment of my invention in which 30 the parts are combined and arranged according to the best mode I have thus far devised for the practical application of the principles of my invention.

Figure 1 is a perspective view of the 35 blank used in the formation of the envelope.

Figure 2 is a perspective view of the envelope complete in its initial form, ready for sealing and looking at the rear of the packet.

Figure 3 is a transverse sectional view of the envelope in its initial form and sealed, the parts being exaggerated for convenience in illustration.

Figure 4 is a longitudinal sectional view of the envelope of Figure 3.

In the preferred form of the invention as 50 shown in the drawings the envelope is made from a single sheet or blank cut and bent or folded on scored lines produced by suitable machinery, and the envelopes are prepared in their initial form by use of suitable and proper machinery.

The blank, as indicated in Figure 1 comprises six leaves indicated as 1, 2, 3, 4, 5, and 6, the two central leaves 1 and 2 forming the pocket, which is open while the envelope is 60 being forwarded to four different destinations, but sealed against access thereto at all times by the presence of the four address leaves during its initial use, and also sealed during subsequent forwarding by the remaining leaves, as will be described. After 65 all of the leaves 3, 4, 5 and 6, or the desired number of them have been used, the return envelope may be returned to the original sender, or be retained by the last receiver 70 as required.

It will be noted that the two central leaves 1 and 2 are scored for folding on line A to form the receptacle or pocket, the leaf 2 being folded up back of the leaf 1 in Figure 75 1, and the leaf 1, which has the address thereon to which the return envelope is to be finally sent has a gummed flap 1^a which is used only when the return envelope, after the four leaves have been detached or dispensed with, is returned to the original 80 sender or to the final receiver. At 2^a the leaf 2, which becomes the back of the envelope, is cut out to facilitate access to the interior of the pocket. By folding the two 85 central leaves at line A, the six leaves become paired, and then the pairs 5—6 and 3—4 are folded on the respective lines D E and B C, covering the address leaf or front 90 1 of the envelope, the free ends S of each of these leaves being gummed, as indicated. Thus the leaf 5 which, like the other leaves is perforated and gummed to form the outer strips S, is also perforated at S' along the fold D, the other leaves 3, 4, 6 being also 95 perforated along the respective folds B C E. The pair of leaves 5—6 are first folded over to the left in Figure 1 and gummed and sealed along edges S, then the pair 3—4 are folded to the right in Figure 1, the free 100 edge of leaf 3 being sealed to the folded edge of leaf 6, and the free edge of leaf 4 is sealed to the free edge of leaf 3. In this manner the four free edges of ends of these leaves 3, 4, 5, 6, are sealed, one pair at the left end 105 of the envelope and the other pair at the right end of the envelope.

At their outer sides, each of the leaves has a gummed tab, indicated respectively as 3^a, 4^a, 5^a, and 6^a, the adhesive or gum being 110 applied at the extreme edge of the tab and the tab being of sufficient length to be bent

or folded over the unsealed flap 1^a and be affixed to the back wall 2 of the envelope. When not in use, or before being used, the tabs 3^a 5^a and 6^a are folded back as indicated in Figure 3, and for initial use, the tab 4^a is folded over the top edges of all the leaves and made to adhere to the back wall 2 of the envelope as in Figure 3. In this instance, and in the three subsequent uses the flap 1^a remains unsealed, but is retained in position by the particular tab that is in use.

In Figures 2, 3, and 4 the envelope is shown prepared for its initial use, and after the tab 4^a in Figure 2 has been bent down over the upper edges and enclosed tabs of the detachable leaves, said tab 4^a is affixed to the back wall 2 as indicated in Figure 3, where the formation and spacing of the parts are exaggerated for clearness of illustration.

As shown in Figure 3 the packet is ready for its first passage through the mails, and when received by the addressee whose name appears on the front of leaf 4, this leaf is detached by severing the tab 4^a and also severing the leaf 4 at its sealed ends S and S', from the packet. By severing the tab 4^a access may be had to the pocket or envelope, and if the packet is being used for tracing a shipment of merchandise on the railroad, for instance, the missive or communication may be withdrawn from the envelope, the proper data placed thereon and the communication returned to the envelope, the flap 1^a still remaining unsealed. By the removal of the first leaf 4, the second address leaf 3 is disclosed, and the second address may be written on this leaf, the tab 3^a withdrawn from the packet and bent over the upper edges of the remaining leaves. The tab 3^a is now affixed to the back of the envelope or leaf 2, and it will be remembered that the ends of the leaf 3 are secured, one end by its fold and the other by adherence to the succeeding leaf 6, the packet being thus sealed at both ends and over the top edge. A postage stamp may be affixed at the upper right hand corner of the leaf 3, and the packet remailed to a second destination. When received at the second destination

the leaf 3 is detached and its tab 3^a broken or torn off giving access to the missive in the pocket. The packet may be sent to the third and fourth destinations under the same conditions, with additional addresses, and after the last address leaf 5 has been removed the front sheet or address sheet 1 of the envelope is disclosed and the envelope is sealed by affixing the flap 1^a to the back wall 2, and the envelope returned to the first sender as first class mail. In this manner the missive or communication may be transmitted to four successive destinations and returned to the original sender in first class condition. And by the use of such an envelope a considerable saving in material, postage and time is accomplished, together with accuracy and facility in dispatching the mail matter.

Having thus fully described my invention, what I claim as new and desire to secure by Letters Patent is—

1. The combination with a pair of main, folded leaves forming the front and back of an envelope with sealed ends, of pairs of separable address leaves folded over the front of said envelope from opposite ends thereof, and means on each address leaf for securing its end, and means on each separable leaf for securing a closure of the envelope.

2. A forwarding envelope comprising a single sheet fashioned with a pair of folded leaves sealed at their ends and forming the front and back of an envelope and a sealing flap on one of said leaves, a separable address leaf folded over the front leaf and attached thereto, and a securing tab on said separable leaf adapted to bend over the top edges of said leaves and be attached to the back of the envelope.

3. The combination with a pair of folded leaves sealed at their ends and forming the front and back of an envelope and a sealing flap on one of said leaves, of two pairs of oppositely folded and sealed separable address leaves, and a sealing tab on each separable address leaf adapted successively to be affixed to the back of the envelope.

In testimony whereof I affix my signature.

ALLEN B. ASHBY.
